UNITED STATES PATENT OFFICE.

CHARLES A. SPAHN, OF NEWARK, NEW JERSEY.

DENTAL TOOL.

No. 831,307.

Specification of Letters Patent.

Patented Sept. 18, 1906.

Application filed April 28, 1906. Serial No. 314,144.

To all whom it may concern:

Be it known that I, CHARLES A. SPAHN, a citizen of the United States, residing at Newark, in the county of Essex and State of New Jersey, have invented certain new and useful Improvements in Dental Tools; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

15 This invention has reference to improvements in tools for dentists' uses; and the invention has for its principal objects to provide a novel construction of tool, made in the manner of forceps, which are to be used in 20 backing false teeth with gold.

25 My present invention has for its principal object to provide a simply-constructed tool of the general character hereinafter more fully set forth, and which is especially adapted for quickly and easily applying gold to the back of a tooth in an efficient manner.

30 Other objects of this invention not at this time more particularly enumerated will be clearly understood from the following detailed description of the same.

35 With the various objects of this invention in view the same consists in the novel construction of dentist's tool, to be hereinafter more fully set forth, for quickly, easily, and efficiently backing false teeth with gold.

40 My invention consists, furthermore, in such novel arrangements and combinations of the parts of the tool, all of which will be hereinafter more fully described and then 45 finally embodied in the clauses of the claim, which are appended to and which form an essential part of this specification.

The invention is clearly illustrated in the accompanying drawings, in which—

45 Figure 1 is a plan view of the dental tool embodying the principles of the present invention. Fig. 2 is a similar view of the same, the handle portions being shown partly broken away and the jaws arranged or set 50 for the first operation in backing false teeth with gold. Fig. 3 is a view similar to that shown in Fig. 2, except that the jaws are ar-

ranged or set to complete the operation of backing false teeth with gold. Fig. 4 is a side elevation of the novel dental tool embodying the principles of the present invention, the handle portions thereof being shown partly broken away. Fig. 5 is a detail longitudinal vertical section of the jaws of the novel dental tool set or arranged as shown in 55 Fig. 2. Fig. 6 is a similar detail vertical longitudinal section showing the dental tool performing the first operation in backing false teeth with gold, and Fig. 7 is a similar view showing the jaws of the novel dental 60 tool arranged to complete the operation of backing false teeth with gold.

65 Similar characters of reference are employed in all of the above-described views to indicate corresponding parts.

70 In the said drawings the reference character 1 indicates the complete tool, which consists, essentially, of a pair of handle portions 2 and 3, pivotally connected at 4 by means of a pin or rivet, substantially as illustrated. 75 The handle portion 2 is provided with a forwardly and preferably downwardly extending jaw member 5, the same being of any desired and suitable configuration. The said jaw member 5 is provided at its outer or free 80 end with a cup-like receiving-socket 6, the said cup-like receiving-socket 6 being adapted to receive and hold a cap or covering 7, preferably made of rubber or a similar resilient material. The said cap or covering 7 is 85 made slightly concave on its outer surface and is provided with a main body portion 8, preferably in the form of a truncated cone adapted to be inserted in the said cup-like receiving-socket 6, and the said cap or covering 7 is further provided with an annularly-extending rim or bead 9, adapted to engage 90 the outer edges of the said cup-like receiving-socket, substantially as illustrated, and the whole providing a suitable supporting member or cushion, as will be clearly evident more particularly from an inspection of Figs. 6 and 7 of the drawings.

95 The handle portion 3 is provided with a forwardly-extending arm 10, provided at its outer or free end with a slot or opening 11, within which is pivotally connected, by means of a pin or rivet 12, the tongue 13 of a forked jaw member 14. The said forked

jaw member 14 is provided with a pair of downwardly-extending arms 15 and 16, the said arm 15 being provided upon its outer or free end with a cup-like receiving-socket 17, the said cup-like receiving-socket 17 being adapted to receive and hold a cap or covering 18, preferably made of rubber or a similar resilient material. The said cap or covering 18 is made slightly convex on its outer surface and is provided with a main body portion 19, preferably in the form of a truncated cone, adapted to be inserted in the said cup-like receiving-socket 17, and the said cap or covering 18 is further provided with an annularly-extending rim or bead 20, adapted to engage the outer edges of the said cup-like receiving-socket 17, substantially as illustrated, and these parts providing a suitable presser or conforming member or cushion. The said arm 16 of the said forked jaw member 14 is provided on its outer or free end with a downwardly-extending pressure-exerting member 21, provided at its end with a small hole or opening 22.

The manner of using the tool for backing false teeth with gold is as follows: In Fig. 6 I have represented a tooth 23, provided with the usual studs or pins 24 for securing the same to a bridge or the like. The said tooth 23 is placed upon the concave surface of the cap or covering 7 of the jaw member 5, and the arm 15 of the forked jaw member 14 is turned so as to form the opposing jaw and provide a forceps-like tool. The cap or covering 18 of the arm 15 is then opposite the cap or covering 7 of the jaw member 5. A sheet or piece of gold is then laid over the back of the tooth and the two caps or coverings 7 and 18 are pressed together with the said tooth between them. The action of the rubber caps or coverings 7 and 18 serves both to hold the tooth in place and at the same time by equalizing the pressure over the surface of the tooth adapts the gold thereto, forcing the gold into all the uneven places in the conformation of the tooth. To complete the operation, the downwardly-extending member 21 is turned into its operative position to form the opposing jaw of the forceps-like tool and the hole or opening 22 therein is placed over the pin or stud 24 of the tooth, and the pressure which is then exerted serves to adapt or press the gold around the base of the pin or stud 24. The false teeth are usually provided with two of such pins or studs 24, and the punch member 21 is so constructed that it will readily pass between them while in operation.

From the above description it is clearly evident that I have provided a simple and inexpensive tool which can be easily and quickly manipulated to efficiently back false teeth with gold, for the purpose above set forth.

I claim—

65

1. A dental tool for backing false teeth with gold, comprising a pair of pivoted handle portions, a forwardly-extending jaw member provided at its free end with a resilient cap or covering connected with one of 70 said handle portions, and a forwardly-extending arm connected to the other handle portion, said forwardly-extending arm being provided with an oscillating forked jaw member, one of the arms of the said forked jaw member being provided at its free end with a resilient cap or covering and the other arm of the forked jaw member being provided at 75 its free end with a pressure-exerting member, substantially as and for the purposes set 80 forth.

2. A dental tool for backing false teeth with metal, comprising a pair of pivoted handle portions, a forwardly-extending jaw member connected with one of said handle portions, and a double-forked swinging arm connected with the other handle portion, said swinging arm being provided with pressure-exerting members, adapted to be alternately moved in position above the supporting member, substantially as and for the purposes set forth. 85 90

3. A dental tool for backing false teeth with metal, comprising a pair of pivoted handle portions, a forwardly-extending jaw member connected with one of said handle portions, a resilient cup-like cushion on said jaw member, a double-forked swinging arm connected with the other handle portion, a conforming member on one of the forked portions of said swinging arm, a resilient cushion on said conforming member, and a second pressure-exerting member on the other forked portion of said swinging arm, said last-mentioned member being provided with a pin-receiving socket, all arranged to be alternately moved in position above the cushion of said supporting member, substantially as and for the purposes set forth. 95 100 105

4. A dental tool for backing false teeth 110
with metal, comprising a pair of handle portions, a supporting member connected with one of said handle portions, said supporting member being provided with a contracted cup-like receiving-socket, a resilient cap inserted in said socket, said cap being provided with an annular bead extending over and in engagement with the outer edge of said receiving-socket, a conforming member connected with the other handle portion, said conforming member being provided with a contracted cup-like receiving-socket, a resilient cap inserted in said socket, said cap being provided with an annular bead extending over and in engagement with the outer edge of said receiving-socket, substantially 125 as and for the purposes set forth. 115
120
125

5. A dentist's tool for backing false teeth

with metal, comprising a pair of pivoted jaw members, a concaved cushion of a soft material upon one of said members, and a convexed cushion of a soft material upon the other member, substantially as and for the purposes set forth.

In testimony that I claim the invention

set forth above I have hereunto set my hand this 26th day of April, 1906.

CHARLES A. SPAHN.
